UNITED STATES PATENT OFFICE

WILLIAM M. MCKENZIE, OF GLENBROOK, CONNECTICUT

SEPARATOR

Application filed April 20, 1929. Serial No. 356,821.

This invention relates to chip separators of the type disclosed in my prior Patent 1,126,240 issued January 26, 1915. One of the objects of this invention is to improve 5 my earlier invention by adapting it for use with an automatic feed mechanism.

A further object of this invention is to so design the air draft exhaust passage that there will be no back draft when the waste 10 material is deposited after being separated from the manufactured product. Another object is to construct the feeder plates so that the material will not be subjected to air pressure until dropped into the forced air draft 15 in order that a solid single blast may act on the material. Further objects and improvements will appear in the specification which describes one embodiment of my invention.

For a more detailed description of the device, I will now refer to my drawings wherein Fig. 1 is a side view of my machine, cut away 20 partially to show a section of the lower and upper vibrating feeder plates. Fig. 2 is a partially cut away plan view of the vibrating 25 feeder plates. Fig. 3 is a perspective diagrammatic drawing of the belt transmission for operating the two feeder plates at different relative speeds from the same power source. Fig. 4 is a side view of my draft 30 control and Fig. 5 is a front view of the same.

Referring more particularly to Fig. 1, reference numeral 10 indicates a base to which is secured the blower 11, which is operable in any desired way, that is, by an electric motor or by belt transmission to produce a forced 35 air draft. In order to control this air draft, I employ a blast gate 12 mounted on an operating shaft 13, and controlled by the hand wheel 14. This hand wheel 14 is set with reference to a pointer gauge 15, and acts to regulate the air draft to a degree depending upon the type of material which is to be 40 acted upon. A set pin 16, mounted in the bearing 17, is adapted to enter various shallow bores 18 in the wheel 14 to hold the same in its set position. It will be noted that I 45 pivot my blast gate at one extreme side of the air chute so that only a single air stream 50 is permitted to ascend the chute. This per-

mits of better regulation and more efficient separation.

The material to be separated is handled through a pair of vibrating feeder plates, one of these plates being shown at 20 and the other at 21. These plates are angularly mounted on vibrator rocker arms 22, carried by the side casing plates 23, there being four rocker arms for each vibrating feeding device. Each of these feeder plates is covered with a series of dome shaped obstructions 24 which act to slow up the movement of the material downward to the discharge end and to spread the material uniformly over the plate. It will be observed that the feeder 55 plate 20 has a discharge opening 25, resting just above the second plate 21. Mounted over this discharge opening are a series of fingers 26 adapted to further slow down the movement of the material from the one feeder 60 plate to the other.

In order to vibrate these plates, there are two eccentrics numbered 27 and 28 shown in Figs. 1 and 3, these eccentrics being adapted to vibrate the feed plates at varied speeds in 75 any of the usual standard ways of submitting an eccentric motion. It is deemed unnecessary to describe this transmission in detail since it forms no part of the present invention and is shown in my original Patent 1,126,240 80 referred to supra.

For a further detailed description of the manner of operating the eccentrics 27 and 28, I will again refer to Figs. 1 and 3. The eccentric 27 adapted to operate the feeder 85 plate 21 is mounted on the shaft 29 carried in bearings 30 and 31. The eccentric 28 adapted to operate feeder plate 20 is mounted on shaft 34 carried by bearings 35 and 36. The counter shaft 38 is mounted rearwardly 90 of shafts 29 and 34 and cooperates with them in a manner to be described presently. The operating shaft 11' of the blower 11 is shown adapted to operate through its pulley 41, the cross belt 42, and the pulley 39 to submit motion to the shaft 38. This shaft 38, in turn, submits motion to the pulley 40 which acts through belt 43 and pulley 32 to actuate the shaft 29 carrying the eccentric 27. The shaft 29, through its pulley 33, belt 44, and pulley 95 45

45 transmits motion to the shaft 34 and the eccentric 38. It will be observed that by means of this system of pulleys and belts, the eccentric 27 will be operated at a considerably lower speed than the blower shaft 11'. Moreover, the eccentric 28 will be subjected to an even further reduction in speed, and will consequently operate at a considerably lower speed than the shaft 27. Thus, 10 the vibrating feeder plate 20 will be vibrated at a lower frequency than the secondary vibrating feeder plate 21.

The vibrating plate 21 is equipped with a discharging end 46, this discharging end being of solid metal, so that the discharged material will not be acted upon by the air draft until it falls vertically past the opening 47 of the air draft passage 19. This permits a single blast to act on the material. 15 A screen 48 in the air passage 19 prevents any material from dropping into the air chute by accident.

In order to obviate any back pressure which might be created by the air draft in carrying 25 away the waste material, I have adapted my device so that a continuous exhaust passage is created for the escaping air draft with provisions for the deposit of the material. This exhaust passage takes the form of a dome shaped head 49 which gives a curved trajectory to the air draft and permits the waste material to be deposited against the dome head while the air draft is given a continuous exhaust passage. Prior to this invention 30 it was customary to run the exhaust against a screen upon which the waste material was deposited. This arrangement caused considerable back draft, especially when the screen became a little clogged with foreign matter.

It will be understood that in operation the material is placed into the initial feeder plate 20 operating at a slow speed under the influence of eccentric 28, the material being fed 45 slowly and spread evenly over the plate by the obstructing portions 24. The material then passes from the initial vibrating plate through the fingers 26 to the secondary vibrating plate 21, operating at a higher speed. 50 There also, it will be slowed up and spread uniformly by the obstructing portions 24 and will finally be permitted to leave through the exit end 46.

It will then drop by gravity past the opening 47 of the air draft passage 19, where it 55 will be acted upon by the air draft adjusted to the proper force by the hand wheel 14 in a manner already described. The chips or waste material will be blown away by the air draft which will escape through the opening 60 50, while the waste matter is deposited against the dome shaped head end 49 and drops vertically into a container placed below the discharge opening 50. The product to be sepa-

rated will, of course, drop by gravity on the chute 51 and into some suitable container.

While I have shown one desirable form of my invention, as improved, it should be understood that other forms may occur within the scope of the appended claims. For a more full and detailed description of the invention, it may be expedient to refer to my prior patent supra, the present specification being drawn to fully set forth merely the improvement over the same.

I claim:

1. In a machine of the class described, a vibrating feeder plate, a second vibrating feeder plate adapted to receive material from said first plate, means for vibrating said second plate at a higher speed than said first plate, an air draft passage, said second plate being adapted to drop material into said passage. 80

2. In a machine of the class described, a vibrating feeder plate, a second vibrating feeder plate adapted to receive material from said first plate, means for vibrating said second plate at a higher speed than said first plate, an air draft and passage therefor, and a discharge end for said second plate located above said air passage and constructed to prevent action of the air draft on the material until discharged from said plate. 85

Signed at Stamford, in the county of Fairfield and State of Connecticut, April, A. D. 1929. 95
